United States Patent Office

Des. 184,981
Patented Apr. 28, 1959

184,981

CHRISTMAS ORNAMENT OR SIMILAR ARTICLE

Jack Burnbaum, Newton, Mass., assignor to Bradford Novelty Co., Inc., Cambridge, Mass., a corporation

Application July 28, 1958, Serial No. 51,946

Term of patent 14 years

(Cl. D29—1)

Fig. 1 is a side elevational view of a Christmas ornament showing my new design;

Fig. 2 is another elevational view looking from the right of Fig. 1;

Fig. 3 is a top plan view; and

Fig. 4 is a bottom plan view thereof.

I claim:

The ornamental design for a Christmas ornament or similar article, substantially as shown.
